CLAIM

The ornamental design for a vacuum cleaner, as shown and described.

DESCRIPTION

FIG. 1 is a front perspective view of the vacuum cleaner showing our new design;

FIG. 2 is a front perspective view of the body portion thereof;

FIG. 3 is a front elevational view of the body portion thereof;

FIG. 4 is a left side elevational view of the body portion thereof;

FIG. 5 is a right side elevational view of the body portion thereof;

FIG. 6 is a rear elevational view of the body portion thereof;

FIG. 7 is a top plan view of the body portion thereof;

FIG. 8 is a side elevational view of the power nozzle and wand thereof;

FIG. 9 is a top plan view of the power nozzle thereof;

FIG. 10 is a front elevational view of the power nozzle thereof;

FIG. 11 is a rear elevational view of the power nozzle thereof;

FIG. 12 is a bottom plan view of the power nozzle thereof;

FIG. 13 is a perspective view of the male end of the power nozzle cord thereof, showing a strain relief ball;

FIG. 14 is a front perspective view of an antidisengagement device for the hose and power nozzle cord thereof; and

FIG. 15 is a rear perspective view of the antidisengagement device.

The hose in FIG. 1 is partially disclosed in broken lines for ease of illustration.

Individual parts of the claimed design have been separately disclosed for clarity of illustration.
